Primary Examiner — Kelley A Donnelly*(74) Attorney, Agent, or Firm* — George Bethel**CLAIM**

I claim the ornamental design for a shelving support post, as shown and described.

DESCRIPTION

FIG. 1 shows a right hand perspective view of the shelving support post.

FIG. 2 shows a front elevation view thereof.

FIG. 3 shows a right elevation thereof.

FIG. 4 shows a rear elevation view thereof.

FIG. 5 shows a left side elevation view thereof.

FIG. 6 shows a top plan view thereof.

FIG. 7 shows a bottom plan view thereof.

FIG. 8 shows a frontal perspective view of the environment in which the shelving support post is used.

FIG. 9 shows a righthand perspective view of an alternative embodiment of the shelving support post.

FIG. 10 shows a front elevation view thereof.

FIG. 11 shows a right elevation view thereof.

FIG. 12 shows a rear elevation view thereof.

FIG. 13 shows a left side elevation view thereof.

FIG. 14 shows a top plan view thereof.

FIG. 15 shows a bottom plan view thereof; and,

FIG. 16 shows a frontal perspective view of the alternative embodiment in the environment in which it is used.

1 Claim, 8 Drawing Sheets(56)
